CLAIM

The ornamental design for a steering wheel for electronic game systems as shown and described.

DESCRIPTION

1. Steering wheel for electronic game systems

1.1 : Front

1.2 : Back

1.3 : Left

1.4 : Right

1.5 : Top

1.6 : Bottom

1.7 : Perspective

The broken lines in the drawings depict portions of the steering wheel for electronic game systems that form no part of the claim.
